UNITED STATES PATENT OFFICE.

JOHN NOVAK, OF CHICAGO, ILLINOIS.

COMPASSES.

1,140,844.

Specification of Letters Patent. Patented May 25, 1915.

Application filed May 4, 1914. Serial No. 836,325.

To all whom it may concern:

Be it known that I, JOHN NOVAK, a citizen of the United States, residing in the city of Chicago, county of Cook, and State of Illinois, have invented new and useful Compasses for use by draftsmen, carpenters, and other craftsmen needing this kind of an instrument at their labor, of which the following is a specification.

10 My invention relates to compasses for draftsmen's or mechanics' use, one of its objects being to provide simple means for maintaining the operating legs of the compass continuously in substantially parallel 15 positions.

Another object is to provide simple means for enabling the compasses to be both quickly and accurately adjusted to any desired spread within their range, and for indicating the spread of the tips of the legs without requiring the latter to be separately measured by means of a rule.

Still another object is to provide simple means for preventing lost motion between 25 the slidably mounted portions of the legs of the compasses and the guides for the same.

Further objects will be apparent from the following specification and from the accompanying drawings, in which:

30 Figure —1— is a front elevation of a pair of compasses embodying my invention. Fig. —2— is a side elevation of the same taken from the right hand of Fig. —1—. Fig. —3— is a plan view of the compasses.

35 Fig. —4— is a fragmentary detail view of the scale forming part of the handle member and of the slide and pivot member engaging the said scale. Fig. —5— is a fragmentary section through one of the pivoted guides 40 carried by the main arms of the compass and the shank of the leg guided thereby.

In the drawings, the compasses include a pair of arms 1 pivotally joined at their upper ends to a common pivot 19, each of 45 said arms having a guide 3 pivoted thereto near the other end of said arm. Slidably mounted in a perforation in each of the said guides is the shank 4 of one of the legs of the compass, each of which legs preferably 50 consists of a shank portion equipped at its

lower end with a socket adapted to receive the upper end of the tip portion of the corresponding leg. The tip portions used may be varied according to the purpose for which the compasses are being used and may be 55 interchangeably secured to the said sockets by means of screws 7. Thus, Fig. —1— shows a pointed tip 8^a mounted upon one shank member 4 and a pen point 8^b mounted upon the other. Each of the said shank 60 portions of the legs is equipped at its upper end with a pivot 5 connecting the same with the other end of a link 2, which link is connected intermediate of its ends by a pivot 6 to one of the arms 1 intermediate of the ends 65 of the latter. The inner ends of the said arms 2 are jointly connected by a pivot-screw carried by a member 11 which is equipped with a vertical slot. Straddling the pivot 19 at the juncture of the arms 1 is 70 a fork comprising a horizontal portion 9 and a pair of vertically depending arms 10, the former of which arms extends slidably through the said slot in the member 11. Attached to the horizontal portion 9 of the 75 said forked member is a substantially cylindrical handle portion 12, which portion 12, together with the said forked member, comprise the handle member of my compasses. It will be obvious from the drawings that upon changing the relative angularity of the arms 1, the links 2 will coöperate with the sliding engagement of the shanks 4 of the leg members and the guides 3 to maintain the said leg members substantially 80 parallel with each other and with the portions 12 and 10 of the handle member; also that in so doing, the relative movement of the arms 1 will be accompanied by a vertical movement of the slot member 11 with 85 respect to the handle portion 10 projecting therethrough. To utilize this movement in saving time for the user of my compasses, I equip at least one face of the handle portion 10 with a scale which may be read along 90 one of the indicating edges presented thereto by the slide or pivot member 11, and which scale is so graduated as to correspond to the spacing between the tips or lower ends 95 of the legs of the compasses. By so doing, 100

I enable the user to readily set his compasses according to this scale, thereby obviating the necessity of his applying the tips of the compasses to a ruler or the like for ascertaining the desired spacing.

5 To avoid accidental shifting of the movable members of the compasses, whereby the spacing of the legs would be altered, I equip the arms 1 with suitable spacer means; as for example, an arcuate spacer 13 slidably mounted in slots in the respective arms 1. In so doing, I preferably equip one of the said arms with a thumb screw 14 whereby the said arm may be firmly locked to the said spacer, and preferably equip the other arm with a worm wheel 15 engaging corresponding teeth upon an adjacent portion of the said spacer member, the latter being continuously held in firm engagement with the said worm by a spring 16 mounted upon the adjacent arm 1. Upon loosening the thumb screw 14, the spacer member will be free to slide through the slot 13 carrying the said screw, so that 10 the compasses may be quickly adjusted to approximately the desired spacing. Then upon tightening the screw 14, the various members of the compasses will be substantially locked against movement, although a limited adjustment may still be secured by manually rotating the worm 15, and by equipping the said worm and the adjacent rack or teeth upon the spacer 13 with relatively small coöperating formations, I am 15 able to provide a quite sensitive adjustment for my compasses while still permitting a quick approximate adjustment thereof.

To prevent a lost motion of the shanks 4 of the leg members with respect to the guides 3, which lost motion might lead to both a rattling and an indefinite or variable spacing of the tips of the compasses, I preferably interpose a spring 17 between the shank 4 and adjacent portion of the arm 1. 20 However, I do not wish to be limited to this or other details of the construction as herein disclosed, as the same might be varied in many respects without departing from the spirit of my invention.

50 I claim as my invention:

1. Compasses, including a handle member, a pair of arms each pivoted at one end thereto, a pair of legs, means slidably connecting said legs respectively with the other ends of said arms, a pair of links pivotally connected at one end to the handle member and at their other ends respectively to the said legs, each of said links pivoted intermediate of its ends to one of the said arms, and spacer means associated with said arms for substantially locking the latter against relative movement.

2. Compasses, including a handle member, a pair of arms each pivoted at one end thereto, a pair of legs, means slidably con-

nnecting said legs respectively with the other ends of said arms, a pair of links pivotally connected at one end to the handle member and at their other ends respectively to the said legs, each of said links pivoted intermediate of its ends to one of the said arms, spacer means associated with said arms for locking the latter against relative movement, and adjusting means associated with the said spacer means for imparting a limited relative movement to the arms when thus locked.

3. Compasses, including a handle member, a pair of arms each pivoted at one end thereto, a pair of legs, means slidably connecting said legs respectively with the other ends of said arms, a pair of links pivotally connected at one end to the handle member and at their other ends respectively to the said legs, each of said links pivoted intermediate of its ends to one of the said arms, and indicating means associated with the handle member and the said links for indicating the spread of the tips of the legs.

4. Compasses, including a handle member, a pair of arms each pivoted at one end thereto, a pair of legs, means slidably connecting said legs respectively with the other ends of said arms, a slide carried by the handle member, and a pair of links pivotally connected at one end to the said slide and at their other ends respectively to the said legs, each of said links pivoted intermediate of its ends to one of the said arms.

5. Compasses, including a handle member, a pair of arms each pivoted at one end thereto, a pair of legs, means slidably connecting said legs respectively with the other ends of said arms, a slide carried by the handle member, and a pair of links pivotally connected at one end to the said slide and at their other ends respectively to the said legs, each of said links pivoted intermediate of its ends to one of the said arms, said handle member equipped with a scale, said slide presenting an indicating edge coöperating with said scale to indicate the spread of the tips of the legs.

6. Compasses, including a handle member, a pair of arms each pivoted at one end thereto, a pair of guides pivotally mounted respectively upon the said arms near the other ends thereof; a pair of legs equipped with shanks slidably fitting the said guides, the said handle member equipped with a portion extending downwardly in the same general direction as the said legs; a pivot member slidably mounted on the said portion of the handle member, and a pair of links respectively connecting the said pivot member and the upper ends of the said legs, each of said links pivoted intermediate of its ends to one of the said arms.

7. Compasses, including a pair of arms pivotally joined at their upper ends, a pair

of links respectively pivoted upon said arms intermediate of the ends of the said arms and said links, a pair of guides respectively pivoted upon the free ends of the said arms;

5 a pair of legs pivoted respectively to the outer ends of the said links and slidably mounted respectively in the said guides;

and pivot means affording a substantially pivotal connection between the inner ends of the said links.
